UNITED STATES PATENT OFFICE.

ALONSITA WALKER, OF WASHINGTON, DISTRICT OF COLUMBIA.

NETHERGARMENT.

1,334,823.

Specification of Letters Patent. Patented Mar. 23, 1920.

Application filed April 23, 1919. Serial No. 292,021.

To all whom it may concern:

Be it known that I, ALONSITA WALKER, a citizen of the United States, residing at Washington, in the District of Columbia, 5 have invented certain new and useful Improvements in Nethergarments, of which the following is a specification.

My invention relates to an improvement in nether garments and there are several objects and among them are the following, first, 10 it takes the place of two other garments, namely a shirt or union suit or in fact any first garment, and a brassière, thereby making two straps on the shoulders unnecessary.

Another advantage, and perhaps the most 15 important object of all, is its function of flattening the bust and holding it in for evening dresses, or in fact any dresses of thin material, with transparent sleeves and 20 yokes and as a result of the application and uniform distribution of tension across the bust and from opposite sides upon a material which is calculated to withstand a certain amount of tension and strain, though 25 light and thin, it has the effect of molding the figure perfectly and gives the feeling of a well fitted lining, and for women who are slightly stout it is particularly adapted because it reduces the fullness of the figure 30 giving it the desired symmetry without distorting the general lines of a graceful figure, and at the same time without sacrifice of comfort or ease and grace in the movement of the body.

With these and other objects in view my invention consists of an under garment provided at the upper edge with a brassière which in reality forms a continuation thereof and may be stitched or otherwise secured 40 thereto or be made as an integral part thereof, of thin and more or less invisible material, substantially non-stretchable lengthwise or across the bust, with a sufficient amount of give up and down so that the 45 leverage or tension, which is applied from opposite ends or in a direction across the bust is resisted and withstood by the material and applied with evenness and uniformity to entire surface of the bust embraced by it, and the degree of pressure is 50 regulated and attained to suit the requirements of the wearer by tapes or ribbons which are connected by substantially triangular tabs at the sides or ends, extending 55 preferably beneath the arms, whence the tapes or ribbons are passed around the back

in opposite directions where they cross and their ends are brought around in front and tied, after being drawn as tight as desired.

In the accompanying drawings,

60

Figure 1, is a front view, and

Fig. 2, is a side view with the figure partly turned to show a portion of the back.

The numeral 1 represents an under garment, in this instance a union suit, although 65 it might obviously be a shirt or in fact any first garment of a woman's wearing apparel. To the upper edge of this article the brassière 2, is stitched or otherwise secured so that the two are part and parcel of each 70 other, which is regarded essential for the reason that the garment 1, is required to hold the brassière down from beneath, with more or less uniformity all the way around.

The extended portion constituting the 75 brassière 2, is preferably made of soft but strong transparent and more or less invisible fabric, such as net, chiffon, or crêpe de chine, of suitable width, and of more than one thickness, if found necessary, to give the 80 required strength, and it is possible and intended, to extend as high or as low as the wearer desires, according to the cut of the neck of the dress to be worn.

Two straps 3, usually of the same material 85 as the brassière, are worn over the shoulders and these two are all that are needed to support garment from above, while a narrow ribbon 4, is threaded through the upper edge and drawn together and tied in a knot 5, as 90 the most convenient, to give the required tension at the upper edge.

At the opposite edges tabs 6, are stitched. These are generally triangular in outline and may be made of the same material as 95 the remainder of the brassière. One side of the triangular tabs 6, is stitched vertically as at 7, substantially throughout the width of the portion 2, and a tape or ribbon 8, extends from the free end of each tab, and is 100 adapted, as shown in the drawings, to be crossed at the back and brought around in front, they being drawn as tight as desired and then tied together in front, in a knot 9, thereby holding the wearer in.

105 It is important that the material forming the brassière portion of the garment be cut and applied lengthwise or across the bust with the strength of the material and so that any give or elasticity be up and down only, 110 as the tension is always across from opposite sides and necessarily so in order to have

the effect of flattening and holding the figure in and so disposed that it will reduce without destroying the natural lines of a well proportioned and graceful figure.

5 Every part of the garment combines and coöperates, in greater or less degree, to the end of accomplishing the purposes of this invention, that is to say, the under garment, the brassière proper, the shoulder straps, the
10 tabs, and tapes or ribbons, all unitedly perform their part in contributing to the success of this article, which is to flatten and confine the figure without losing any of the natural grace and symmetry of the form, all
15 of which is accomplished with perfect comfort to the wearer, without the necessity of increasing the number of garments worn, but by actually reducing them.

20 The invention is simply a combination under garment, the two being, in effect, inseparable, when in use, and the lower garment a union suit, a shirt or its equivalent and serving as a means of anchorage as it were for the brassière from or along its entire lower
25 edge.

I claim—

1. A nether garment which includes any first garment having a brassière attached to, and forming a continuation of, its upper
30 edge by means of which it is held from be-

neath, it extending over the bust, with slender straps extending over the shoulders and attached to the upper edge of the garment thereby supporting it from above, and tension means attached to the garment at opposite points and extending rearwardly in a direction beneath the arms so that when tightened they apply pressure upon the bust from above and downwardly with a flattening effect which holds the bust down. 35 40

2. A nether garment which includes any first garment, having a brassière attached to and forming an extension of its upper edge, the extreme upper edge of which extends no higher than the arms of the wearer, tabs 45 having their inner edges attached transversely at opposite sides of the brassière with their free ends extended outwardly or in a direction toward and beneath the arms, and tapes or ribbons secured to the outer 50 ends of these tabs and of sufficient length to extend around the wearer's back where they are crossed and thence around to the front at the waistline where they are adapted to be fastened together whereby to maintain a 55 flattening and compressing effect upon the bust of the wearer.

In testimony whereof I affix my signature.

ALONSITA WALKER.
